Specification of Letters Patent.

Patented Feb. 4, 1919.

Original application filed February 24, 1910, Serial No. 545,599. Divided and this application filed March 30, 1916. Serial No. 87,717.

To all whom it may concern:

Be it known that I, HOWARD D. COLMAN, a citizen of the United States, residing at Rockford, in the county of Winnebago and 5 State of Illinois, have invented certain new and useful Improvements in Winders, of which the following is a specification.

This invention relates to machines for re-winding yarn from bobbins onto spools, 10 cheese cores or other suitable yarn carriers.

One of the objects of this invention is to provide means for throwing the cheese, spool or the like, out of operation when the thread being wound is exhausted through breakage 15 of the thread or through the complete unwinding of the bobbin.

Another object of the invention is to provide means for braking the spool or cheese upon the exhaustion of the thread.

20 Another object is to provide means for clamping the exhausted thread in order to hold the end thereof in convenient position for subsequent operations thereon.

Another object is to produce means for 25 forming a supply loop of thread between the detector and the clamp in order that the end of the thread, when exhausted, shall not pass the clamp before the clamp has closed.

A further object is to provide means for 30 holding the yarn-traversing element out of operation while the cheese or spool is in thrown-out position.

In the accompanying drawings Figure 1 is 35 a transverse vertical sectional view through a machine embodying the features of my invention. Fig. 2 is a detail of the means for supporting a certain shaft of the machine. Fig. 3 is a fragmental side elevation, with 40 parts in section. Fig. 4 is a fragmental transverse sectional view upon a larger scale than that of Figs. 1 and 2. Fig. 5 is an elevation of a pair of bobbin-holders. Fig. 6 is a top plan view of said pair of bobbin-holders. Fig. 7 is a fragmental perspective 45 view of a shield and one of the reserve-thread clamps. Fig. 8 is a front view of one of the groups of thread-controlling devices. Fig. 9 is a vertical sectional view taken in the plane of dotted line 9-9 of Fig. 8. Fig. 50 10 represents a detector fork and a stop for controlling the movement of said fork into operative position. Fig. 11 is a section on

line 11-11 of Fig. 9. Figs. 12 and 13 are side views representing different positions of the thread-controlling devices. Fig. 14 55 illustrates one of the spool supports and related devices. Fig. 15 is a sectional view of said parts, the view being taken in the plane of dotted line 15-15 of Fig. 18. Fig. 16 is a section on line 16-16 of Fig. 14. 60 Fig. 17 is a fragmental view of a means for preventing upward displacement of the spool spindle. Fig. 18 is a top plan view of the spool support and related parts. Figs. 19 and 20 are details of a guide for a build-bar. Figs. 21 and 22 are, respectively, a 65 front elevation, partly in section, and a top plan view of the spool support and related devices, showing a different form of brake from that illustrated in Figs. 14, 15 and 18. 70 In Figs. 21 and 22 the brake is represented as in the released position. Fig. 23 illustrate a means for holding the spool out of contact with the spool-rotating means. 75

This application is a division of application Serial Number 545,599, filed February 24th, 1910, (Patent No. 1,183,276,) and a continuation in part of application Serial Number 167,703, filed July 31st, 1903, (Patent No. 1,187,971.) The machine shown in 80 Patent No. 1,183,276 comprises a spooler, that is to say, a machine for winding yarn from bobbins onto spools, and a winder-tending mechanism arranged to travel along the spooler and tie the ends of the yarn on 85 reserve bobbins to the ends of the yarn on the spools. It will be understood, however, that certain of the improvements disclosed in the present application are adapted for use in winders of other types. 90

The embodiment herein shown of my invention comprises a framework providing two parallel "sides," each side being equipped with means for supporting bobbins and means for supporting and rotating 95 spools. As shown in Figs. 1 and 3, the framework of the machine may comprise a number of transverse frames 1 rigidly united by suitable longitudinal members, as, for example, the rods 2 and the two angle-irons 3. 100

The bobbins may be supported in any ordinary or preferred way; for example, they may be non-rotatably mounted for the drawing of the yarn off the tips of the bob-

bins or they may be rotatably supported for the unwinding of the yarn from the sides of the bobbins. The present drawings illustrate bobbin-holders of the type shown in 5 Patent No. 1,045,879, dated Dec. 3, 1912. Each winder unit comprises two bobbin-holders 9 (Fig. 5) located one above the other, the top bobbin-holder being offset sufficiently to provide space for a thread 10 extending from a bobbin in the lower bobbin-holder. The base 8 of each pair of bobbin-holders is mounted upon a rod 4 which is carried by arms 5 fixed to and rising from bars 6 that are rigidly attached to arms 7 15 on the frames 1.

The build motion comprises, in this instance, two angle-iron rails 13 (Figs. 1 and 3) fixed to slides 14 which are slidably mounted upon vertical guides 15 attached to 20 the frames 1. To a rock shaft 16 are fixed a suitable number of levers 17 which are connected by means of links 18 to the slides 14. The shaft 16 is rocked to raise and lower the build-rails 13 alternately by means of a cam 25 19 (Fig. 3) engaging a roller 20 on an arm 21 fixed on said shaft, and a weight 22 carried by an arm 22^a on the shaft 16, the weight holding the roller against the cam. The cam is mounted on a shaft 23 which carries 30 at one end a spur gear wheel 24 meshing with an intermediate gear 25, the latter meshing with a pinion 26 fast on a shaft 27. On the shaft 27 is a worm wheel 28 meshing with a worm 29 on a vertical shaft 30. 35 Power to rotate the shaft 30 is derived from any suitable source, as a countershaft (not shown) geared to a shaft 31 which is coupled to the shaft 30.

For each spool there is a build-bar 32 (Fig. 40 4) the lower end of which carries a pin 33 resting on the build-rail 13, the yarn being guided by the bent upper end of the build-bar. As the rails 13 alternately rise and descend, the bars 32 direct the yarn to various 45 heights upon the spools, thus causing the yarn to be wound evenly on the spools.

The spools may be rotated in any usual or desired manner; herein they are shown as rotated by contact of the yarn mass with a 50 continuously-moving endless belt 34 carried by a pulley 35 fixed on the shaft 30 and a similar pulley (not shown) at the other end of the machine frame. Intermediate said pulleys the belt is confined between idlers 36 55 placed at suitable intervals at opposite sides of the belt. See Fig. 3.

Referring now to Fig. 1: 37 are laterally-extending arms attached to the frames 1 and supporting bars 38. Brackets 39 (Figs. 1 60 and 2) are fixed to the outer end of the arms 37 and at intervals to the bars 38, and in these brackets are journaled shafts 40 which are rotated by any suitable means, as, for example, by means of sheaves 41 and belts 42 65 running to any convenient source of power,

such as the countershaft before referred to. On each shaft 40 are fixed peripherally-grooved tension-reducing guide-rolls 43 (Figs. 8 and 9), one for each spool, over which rolls the yarn runs in passing from 70 the bobbins to the spools. The peripheral speed of the rolls 43 is greater than the speed of winding, hence, while said rolls are incapable of positively feeding the yarn, they reduce the tension of the yarn in the region 75 between the rolls and the spools, and thus insure that any breakage of the yarn due to weakness shall occur between the bobbins and the rolls. 44 (Figs. 8 and 9) are thread-guides fixed upon the bars 38, the running 80 threads extending through said guides.

When the thread exhausts, the end of the thread would become wound upon the spool unless prevented from so doing, and the thread-end would have to be found before 85 the thread could be tied to the thread of the reserve bobbin. In order to prevent the exhausted thread from being wound on the spool, the rotation of the spool is stopped by means of a brake hereinafter described. 90 To keep the exhausted thread under control and prevent it from jumping out of its proper position, I provide means for clamping the thread when it exhausts. Adjacent to each of the guides 44 is a thread clamp, 95 the stationary member of which clamp consists, in this instance, of a round rod 45 (Fig. 8) lying in a rabbet formed in the bar 38 and attached to a bracket 46 screwed to said bar. The movable member 47 of 100 the clamp is mounted upon a pivot 48 and is adapted to swing down into position to clamp the thread against the member 45. A coiled spring 49 (Fig. 9) bears against one side of the clamp member 47. To an 105 arm 50 of the bracket 46 is pivoted at 51 a lever 52 having thereon a finger 53 lying within an opening 54 in an arm 55 of the clamp member 47. Means to be later described tends at all times to swing said 110 lever and close the thread clamp. The lever 52 is held against operation until the thread running through the adjacent guide 44 exhausts, by means comprising a fork 56 fixed on a rock shaft 57 supported by the 115 bracket arm 50, said fork consisting of a short tine 58 and a longer tine 59 between which the lower end of the lever 52 normally lies. Fixed upon the shaft 57 is a detector fork 60 having bent tines 61 that are arranged to alternate with fingers 62 forming a grid which is mounted on an arm 63 that is fixed to the bracket 46. On its way to the spool, the running thread extends from the active bobbin, over a guide 120 pin 64, between the tines 61 and the fingers 62, and part way around the tension-reducing roll 43, the tension on the thread due to the drag of the bobbin preventing the detector fork 60 from swinging far enough 125 130

to the right (Figs. 4 and 9) to permit the lower end of the lever 52 to slip past the short tine 58 of the fork 56. To prevent interference between the active thread and 5 the reserve thread, said threads are caused to pass at opposite sides of a finger 64^a fixed to the pin 64. 65 are stops for limiting the swinging movement of the detector fork 60.

A stop 254 (Fig. 10) is pivoted on the 10 lower side of the bar 38 in position to lie in the path of movement of the detector fork 60 when the latter is moving toward its operative position. An arm 255 on said stop carries a pin 256 arranged to be engaged by a cam (not shown) on the carriage of the traveling winder-tending mechanism, to swing the stop out of position to interfere with the movement of the detector fork. A spring 258 tends to swing the stop 15 into operative position.

Referring to Figs. 4 and 7, a shield 66 is fixed to the bar 38. In the vertical plane of each roll 43, a slot 67 is formed in the shield, for the entrance of the threads, as 25 will appear more fully hereinafter.

For the free end of the yarn on each reserve bobbin there is provided a spring clamp 68 attached to the bar 38. A projection 68^a (Fig. 8) prevents the thread from 30 being inserted too far back into the clamp, and insures that the thread shall have a definite operative position with relation to the device (not shown) for taking the thread out of the clamp.

35 Between the tension-reducing roll 43 and the thread-clamp 45 47 the yarn passes around an idler roller 69 (Fig. 8), whereby a reserve-supply loop is formed in the thread to give sufficient length between the 40 bobbin-holder and the spool so that the spool may be stopped before the end of the thread, when exhausted, has passed too far to be operated upon by the winder-tending mechanism. Said roller is mounted upon a 45 slide 70 arranged for vertical movement upon a guide bar 71, loops or straps 72 (Fig. 4) on said slide serving to guide the latter in its movements along the guide bar. The idler roller 69, is inclosed within a housing 50 73 having a slot 74 (Fig. 8) in its walls to permit the thread to run in contact with the roller, said slot having a flaring entrance portion 75. Upon the upper end of the slide 70 is a deflector 76 the purpose of 55 which will appear hereinafter. Normally the slide 70 rests upon the rail 6, as shown in Fig. 4. The device 69-70 will be hereafter termed the looper. It has a lug 241 (Fig. 4) by means of which it is raised to 60 the position shown in Fig. 13 when a loop is to be formed in a new thread.

Secured to the angle-irons 3 are brackets 77 (Figs. 14 and 15) having alined bearings 78 79 thereon. 80 is a shaft, the upper portion of which is supported in the bearing 65

78. Upon the lower part of the shaft is loosely mounted a sleeve 81 which is rotatably mounted in the bearing 79.

The spool-spindle is carried by a frame 83 comprising the vertical sleeve 84 and the 70 arms 85 86, said arms being loosely mounted on the upper end of the shaft 80 and the sleeve 81, respectively. Fixed to the shaft 80 is a finger 87 (Fig. 14) carrying a pin 88. A coiled spring 89 surrounds the shaft 80 75 and the sleeve 81 between the bearings 78 79 and bears at its ends against the pin 88 and a pin 90 set in a ratchet disk 82 (Figs. 15 and 16), said disk being rigid with the sleeve 81. The tension of the spring may 80 be adjusted by rotating the disk 82, the disk being held in the desired position by means of a pawl 91 which is mounted on an arm 86^a which is rigid with the arm 86. On the upper end of the shaft 80 is fixed a crank 85 arm 92. A link 93 is attached at one end to said crank arm and at its other end to a slide 94 (Fig. 11), which slide is movable longitudinally of a slotted guide bar 95 fixed to the bracket 46. To the lower end of the 90 slide 94 is attached a link 96 (Fig. 9) that is connected to the lever 52 at 97. When the fork 56 holds the lever 52 from movement, the shaft 80 cannot rotate, hence the pin 88 forms a stationary abutment for the spring 95 89, which latter tends to swing the frame 83 in the direction to throw the spool against the constantly moving belt 34.

The spool-spindle 98 is rotatably mounted in the sleeve portion 84 of the frame 83. 100 Lubricating oil may be admitted to the interior of the sleeve 84 through ducts 100 101 (Fig. 17). 102 is a cap for closing the inlet end of the duct 101, said cap being fixed to an arm 103 which is pivoted at 104.

105 The spool rests upon a disk 105 fixed to the spindle 98, said disk having studs 106 thereon to fit into recesses in the lower end of the spool and thus prevent rotation of the spool with relation to the disk 105. Said 110 disk has a peripheral flange 107 arranged to be engaged by a suitable brake device, as, for example, a shoe 108 (Figs. 15 and 18) attached to a stem 109 which is pivotally connected with the crank arm 92 concentrically to the shaft 80. The brake shoe is 115 slidable between lugs 110 (Fig. 18). When the detector fork 60 permits the shaft 80 to move, the spring 89 turns said shaft and presses the brake shoe 108 against the flange 110, thereby stopping the rotation of the spool. Both ends of the spring are now bearing against the frame 83, consequently 120 said spring exerts no tendency to swing the frame. Immediately upon the application of the brake, the momentum of the spool is absorbed by the pivoted frame 83, and said frame immediately swings away from the belt 34. The momentum of the spring 89 and the arm 92 also plays a small part in 125 130

causing the swinging movement of the spool frame 83. To hold the spool in withdrawn position, collars 111 and 112 (Fig. 14) are fixed to the bearing 79 and the arm 86, respectively, said collars having upon their opposing faces low teeth which are brought into mesh, as shown in Fig. 23, when the spool leaves the belt, thereby releasably locking the spool out of contact with the belt. The teeth on the collars 111 and 112 permit of a little play between them.

In Figs. 21 and 22 I have shown a band brake 113 which may be used in lieu of the brake shoe 110. One end of the brake band is attached to the arm 85 and the other end to the crank arm 92.

To counteract any tendency of the disk 105 to rise during its rapid rotation, a hook 103^a (Fig. 17) is provided upon the arm 103, said hook overlying an inturned flange 107^a on the flange 107.

During the resetting of the detector mechanism by the winder-tending mechanism hereinbefore alluded to, the latter holds the spool out of contact with the belt 34 by means of a cam (not shown) acting upon an arm 114 fixed to the frame 83.

Referring to Fig. 5, the build-bars 32 are guided in their vertical movements by means of guides 115 116, the guides 115 being rigidly fixed to the brackets 77. It is desirable to retain each build-bar in its most elevated position during the operation of tying a reserve bobbin to the yarn on the spool, to attain which end I provide in the present embodiment the following-described means: The guide 116 is pivoted at 117 (Fig. 14) and is normally held in such position that the build-bar can pass freely through the guide, by the finger 87, the guide having a stem 118 (Fig. 20) which rests on the finger. When the finger is withdrawn by the brake-applying movement of the shaft 80, the guide 116 drops into the position indicated in Fig. 19 whereupon the downward movement of the build-bar is prevented by reason of binding of said bar in the guide. It will be seen that should the finger 87 be withdrawn when the build-bar is not in its most elevated position, the guide 116 does not prevent the build-bar from being raised by the build-rail 13, but engages the bar as soon as the latter starts to descend from its highest position. When the finger 87 is returned to its normal position, the inclined surface 119 (Fig. 20) on said finger engages the pin 118 and raises the guide 116 into the position represented in Figs. 14 and 20. 120 (Figs. 14 and 22) is a stop pin to limit the upward movement of the guide, and thus prevent the build-bar from frictionally raising said guide during the normal operation of the build-bar.

In use, the operator keeps each pair of bobbin-holders supplied with a reserve bob-

bin, the end of the yarn on said bobbin being placed in the adjacent clamp 68. Practically all exhausts are caused by the emptying of the bobbin, yarn breakages being relatively infrequent.

Referring to Fig. 9, the running thread holds the detector fork in the position shown in said figure, the detector fork being pressed against the thread by the spring 89 acting through the finger 87, the shaft 80, the arm 92, the link 93, the slide 94, the link 96, the lever 52, and the fork 56. When the thread exhausts, the detector fork moves into the position shown in Fig. 12, thus allowing the lever 52 to escape from the fork 56, the spring 89 causing the brake to be applied to the flange 107, and the spool frame 83 swinging away from the belt 34. The teeth on the collars 111 112 (Fig. 23) hold the spool frame in such withdrawn position. When the lever 52 moves into the position shown in Fig. 12, the clamp member 47 is swung down into position to clamp the exhausted thread.

When the traveling winder-tending mechanism reaches the unit, a cam (not shown) on the carriage of said mechanism acts upon the pin 256 (Fig. 10) to swing the stop 254 to the right. Another cam 253 (Fig. 13) on said carriage pushes the slide 94 forward on the guide 95 and thus moves the detector fork 60 into the position shown in Fig. 13, at the same time moving the clamp member 47 up into thread-receiving position. Mechanisms on the carriage unite the reserve thread and the exhausted thread. Other devices (237 and 240, Fig. 13) on the carriage raise the looper 69—70 up through an opening 66^a (Fig. 7) in the shield 66, and into the position shown in Fig. 13, the inclined surface 76 pushing the thread aside. The looper is then permitted to drop upon the thread, the latter passing through the entrance 75 (Fig. 8) into contact with the roller 69. The descent of the looper draws the threads away from the vicinity of the knotter and takes up the slack in said threads. A cam on the carriage then permits the spring 89 to swing the detector fork lightly against the new thread, said fork resting against the stop 254 (Fig. 10). As the rear end of the carriage passes the unit, the cam 261 on the carriage withdraws the stop 254, thereby permitting the fork 260 to rest wholly upon the thread. A device on the carriage now permits the looper to descend still farther, whereby the looper draws thread from the bobbin, thus setting the bobbin in rotation. While the bobbin is thus rotating, a cam on the carriage permits the spring 89 to throw the spool into driving contact with the belt 34.

While the present embodiment of the invention has been described with considerable particularity, it will be understood that

the invention is not limited to the construction and arrangement of mechanisms shown.

In certain of the claims I have used the 5 term "a winding couple" to indicate two yarn masses, one of which is being rewound upon the other, without regard to the character, size or location of such masses. The 10 terms "thread" and "yarn" are to be construed as including similar material.

I claim as my invention:

1. A winder having in combination, means for rotating a receiving container, means for braking the container, a spring for actuating the brake, a thread clamp also actuated by said spring to clamp the end of the thread that is wound on the receiving container, and a detector for normally restraining the spring.

20 2. A winder having, in combination, a pivoted spool-support; means for rotating a spool carried by said support; a brake for the spool; a spring for swinging said spool-support to place the spool in operative relation with the rotating means and for actuating the brake; and means for controlling said spring.

30 3. A winder having, in combination, a bobbin support, a pivoted frame, a container-supporting member rotatably carried by said frame, means for rotating a container carried by said member to unwind yarn from a bobbin on the bobbin support onto the container; a brake device adapted 35 to engage said member; a spring exerting its force upon said brake device and said frame; and means for controlling said spring.

40 4. A winder having, in combination, a bobbin support, a suitably supported rock shaft; a frame pivoted on said shaft; a container-supporting member rotatably carried by said frame; means for rotating a container carried by said member to unwind 45 yarn from a bobbin on the bobbin support onto the container; a brake device adapted to engage said member and attached to said shaft; a spring bearing at its ends upon said shaft and said frame; and means for holding 50 said shaft from movement by said spring.

55 5. A winder having, in combination, container-rotating means, a container support arranged to swing to move the container into and out of contact with the container-rotating means, and a brake for the container, said brake being mounted on said support, the momentum of the braked container causing the container support to withdraw from the rotating means.

60 6. A winder having, in combination, container-rotating means, a container support arranged to swing to move the container into and out of contact with the container-rotating means, and means for braking the 65 container, the momentum of the braked con-

tainer causing the container support to withdraw from the rotating means.

7. A winder having, in combination, container-rotating means, a container support arranged to swing to move the container into 70 and out of contact with the container-rotating means, means for braking the container, the momentum of the container causing the braked container support to withdraw from the rotating means, and means 75 for holding the container support in such withdrawn position.

8. A winder having, in combination, a bracket; a rock shaft mounted in said bracket; a container-carrying frame pivotally supported on said shaft; container-rotating means; a torsion spring surrounding said shaft, one end of said spring bearing upon said frame and the other end bearing upon said shaft; said spring tending to 80 swing the frame in the direction to place the container in contact with the container-rotating means; a container-brake actuated by the shaft; and means for holding said shaft against rotation by said spring.

9. A winder having, in combination, a pivoted support, a spindle rotatably carried by the support; a spool-supporting disk on the spindle, means for rotating a spool carried by said disk; a brake to engage the 95 disk; a spring for swinging said support to place the spool in operative relation with the rotating means and for actuating the brake; and means for controlling said spring.

10. A winder having, in combination, a bracket; a rock shaft mounted in said bracket; a container-carrying frame pivotally supported on said shaft; a container-brake actuated by the shaft; container-rotating means; means tending to rock said 100 frame to place the container in engagement with the container-rotating means and also to rock said shaft; and means for controlling said rocking means.

11. A winder having, in combination, a bracket; a rock shaft mounted in said bracket; a container-carrying-frame pivotally supported on said shaft; container-rotating means; a torsion spring surrounding 115 said shaft, one end of said spring bearing upon said frame and the other end bearing upon said shaft; collars fixed to said bracket and said frame respectively and surrounding said shaft, the contacting faces of said collars having teeth adapted to mesh to hold said frame yieldingly against swinging movement; and means for controlling said spring.

12. A winder having, in combination, two 120 guides for the thread being wound, a normally-stationary device movable into position to engage the thread at a point between the guides and movable into position to draw the thread into the form of a reserve-supply 125

65

loop and means for moving said device into position thus to engage the thread.

13. A winder having, in combination, two guides for the thread being wound, a normally-stationary device movable into position to engage the thread at a point between the guides and movable into position to draw the thread into the form of a reserve-supply loop, and a deflector on said device to push 10 the thread aside when said device is moving into position to receive the thread.

14. A winder having, in combination, means for supporting a winding couple, a device to throw out of operation the receiving member of the couple, a device to clamp 15 the end portion of the thread attached to said receiving member, a spring tending to actuate said devices, and a detector engaging the thread of the couple and serving to restrain 20 the spring, the clamping device being located between the detector and the receiving member of the couple.

15. A winder having, in combination, a suitably supported rock shaft; a spool-25 carrying frame mounted on said shaft; spool-rotating means; means for rocking said shaft; a build-bar; means for moving said bar; means for guiding said bar, said guiding means comprising a member adapted 30 to hold said bar from movement; and means on said shaft for operating said member.

16. A winder having, in combination, a suitably supported rock shaft; a spool-carrying frame mounted on said shaft; spool-rotating means; means for rocking said shaft; a build-bar; means for moving said bar; means for guiding said bar comprising a pivoted guide through which said bar extends; and a member on said shaft for supporting 40 said guide in position to permit the bar to move freely therein, said member being withdrawable in the rocking movement of said shaft.

45 17. A winder having, in combination, means for supporting a winding couple, a device to clamp the thread of the couple, a pivoted detector, the clamping device being arranged to clamp the thread at a point between 50 the detector and the receiving member of the couple, a lever connected to the detector and the clamping device, and a spring tending to move the lever to operate said detector and clamping device.

55 18. A winder having, in combination, means for supporting a bobbin, means for rotating a yarn mass to draw thread from the bobbin, a detector engaging the thread, and a clamp to hold the end of the thread on 60 the yarn mass when exhausted, said clamp being controlled by the detector.

19. A winder having, in combination, means for supporting a winding couple, a detector engaging the thread of the couple, and a clamp arranged to clamp the thread 65

at a point between the detector and the receiving member of the couple, said clamp being controlled by the detector.

20. A winder having, in combination, means for supporting a thread supply, 70 means for rotating a receiving yarn mass to draw yarn from the supply, a clamp to hold the thread extending to the receiving yarn mass, and a device to form a reserve-supply loop in the thread between the supply and the clamp. 75

21. A winder having a thread clamp, a guide for the thread, and means for forming a loop in the thread between the guide and the clamp. 80

22. A winder having, in combination, means for supporting a winding couple, a detector engaging the thread of the couple, a clamp arranged to clamp the thread at a point between the detector and the receiving member of the couple, said clamp being controlled by the detector, and a device to form a supply loop in the thread between the detector and the clamp. 85

23. A winder having, in combination, 90 means for supporting a winding couple, a detector engaging the thread of the couple, a clamp arranged to clamp the thread at a point between the detector and the receiving member of the couple, said clamp being controlled by the detector, a device to form a supply loop in the thread between the detector and the clamp, and a tension-reducing roll over which the thread runs between the detector and the loop-forming device, 100 said roll being driven at a higher surface speed than the speed of the yarn. 95

24. A winder having, in combination, means for winding yarn upon a spool; a build-bar; means for moving said build-bar; and means for detaining said build-bar at the upper end of its movement upon the exhausting of the yarn. 105

25. A winder having, in combination, a vertically movable build-rail, a plurality of 110 build-bars arranged to be raised by said rail, and means for preventing downward movement of said build-bars.

26. A winder having, in combination, a build-rail, a plurality of build-bars arranged to be raised by said build-rail, and means individual to each build-bar for preventing downward movement of such bars. 115

27. A winder having, in combination, a plurality of individual building elements, 120 a common means for raising said elements, and individual means for preventing downward movements of said building elements.

28. A winder having, in combination, two guides arranged one above the other, a build-bar extending through said guides, one of 125 said guides being movable into position to cause the bar to bind therein, and means for operating said guide.

29. A winder having, in combination, a 130
